UNITED STATES PATENT OFFICE.

GEORGE W. RANKIN, OF JERSEY CITY, NEW JERSEY, ASSIGNOR TO GLOBE FIRE APPARATUS COMPANY, OF JERSEY CITY, NEW JERSEY, A CORPORATION OF NEW JERSEY.

CHEMICAL FIRE-EXTINGUISHER.

No. 923,076.

Specification of Letters Patent.

Patented May 25, 1909.

Application filed September 18, 1908. Serial No. 453,661.

To all whom it may concern:

Be it known that I, GEORGE W. RANKIN, a citizen of the United States, residing at Jersey City, in the county of Hudson and State of New Jersey, have invented certain new and useful Improvements in Chemical Fire-Extinguishers; and I do hereby declare the following to be a full, clear, and exact description of the invention, such as will enable others skilled in the art to which it appertains to make and use the same.

My invention relates to improvements in chemical fire extinguishers, operated by hand, and the object of my invention is to produce a simple device of this character, whereby gas or water charged with gas may be directed upon the flames, and in which a mechanical escape vent is provided.

With this object in view, my invention consists of the construction and combinations of parts as hereinafter described and claimed.

In the accompanying drawings—Figure 1 is a vertical cross section of a chemical fire extinguisher with my improvements applied thereto. Fig. 2 is a cross section of the upper part of a modified form, the acid bottle having been inverted, and Fig. 3 is a cross section of the modified form, after the acid bottle has been inverted, and showing the parts in position ready to deliver gas upon the fire.

a denotes the body of the fire extinguisher of the usual cylindrical form, having an upwardly projecting screw-threaded extension *b* at its top, on which is screwed the cap *c*.

d represents the discharge hose, which is connected with a pipe *f* running nearly to the bottom of the body *a*.

To the cap *c* is secured by means of screws or otherwise, the open frame *g*, consisting of two upright pieces connected together by a cross piece at the bottom. In these upright pieces, is pivotally mounted the frame for carrying the acid bottle, the lower part of which is rectangular in shape, and three of the sides of which extend about half way up the bottle *h*. The part *i* of the frame is made of resilient material, so that the bottle may be easily inserted or removed, and the part *j* of the frame extends nearly the full length of the bottle and terminates in a curved weight *k*, which partially encircles the neck of the bottle. The parts are so arranged that the weight *k* will turn the bottle down, as shown

in Fig. 2, when it is desired to use the apparatus.

The cap *c* is provided with a downwardly projecting central extension *m*, closed by a stuffing nut *n*, suitable packing being provided and through this extension runs a rod *o*, which is provided with a metal cap *p* on its lower end, having a soft packing *q* which is adapted to engage with and close the upper end of the bottle when it is in its upright position, as shown in Fig. 1.

To the upper end of the rod *o* is attached a horizontal arm *r*, extending in both directions from said rod, and the ends of this rod *r* are adapted to engage with, or be disengaged from bent stops *s*, projecting upwardly from the cap *c*, one or more of which stops may be used.

The upper part of the rod *o* is perforated, as shown at *t*. The perforation passes centrally down through the tube for a certain distance, and then out through its side, as shown in Fig. 1, terminating in a horizontal perforation *u*. The parts are so proportioned that when the rod *o* is pressed downwardly so that the packing *q* will engage the top of the bottle, as shown in Fig. 1, the perforation *u* will be below the extension *m*, thus allowing a free escape for the gas or air. This mechanical escape vent passing through the pull device, which is operated to set the machine in operation, is of great importance.

In the position shown in Fig. 1, it permits air to pass freely in and out of the body *a*, which thereby prevents siphoning. This overcomes a great fault which is incident to siphon extinguishers which do not allow for the expansion of air. No discharge means are provided in such extinguishers except through the outlet hose *d*. To prevent leaking, stop valves are sometimes put on the end of the hose, but even under this condition, the hose is filled with water nearly all the time, which rots the hose and corrodes the stop valve so that it cannot be relied upon to operate easily when needed. Some manufacturers advise the water to be put in the extinguisher at a temperature of 90 or 95° F., as the water is then not likely to absorb any more heat, but after the water cools, this does not prevent siphoning in the apparatus. In my device, the inside opening *u* is closed when the machine is operated, by being pulled up into the stuffing box. A double protection is offered against the escape of

gas through the cap, because the top of the metal casing *p* is pulled up against the stuffing box, thereby forming a tight seal. A still further use of this gas vent is that it acts

5 as a safety valve after the machine has been in operation, in which case the rod *o* is pushed down and confined in the position shown in

Fig. 1. The interior of the body *a* is then in connection with the atmosphere, and any gas 10 which may be in the body *a* is permitted to escape, thus protecting the operator from injury which might be caused by unscrewing the cap while there is still gas pressure in the apparatus.

15 An advantage of my construction is that it is only necessary to move a single part, the rod *o*, to start the evolution of gas. Thus there is practically no difficulty due to corrosion, and if the operator fails to pull the

20 rod *o* up far enough, the pressure of the gas generated will force the part *p* tightly against the extension *m*.

Instead of using a hose, as shown in Fig. 1, a revoluble discharge nozzle *v*, as shown in

25 Figs. 2 and 3 may be used. This nozzle is bent and its inner end is provided with a stuffing box and is in communication with the pipe *f*. The nozzle *v* is bent and is provided with a handle *w*, so that it may be rotated, as desired. A further advantage of

30 this construction is that the escape valve can be used as a nozzle to direct gas, unmixed with water, upon a flame. The parts being in the position shown in Fig. 3, and the body

35 *a* being held nearly vertical, the operator

puts his finger over the outlet end of the nozzle *v*, and the gas generated in the machine

issues unmixed with water through the perforation *t*. It often happens that it is very

40 desirous in small fires to use gas alone. Thus

where expensive curtains, draperies, paint-

ings, bric-a-brac, etc. would be ruined or injured by having water thrown upon them, the fire may oftentimes be put out by the use of gas alone, without injury.

45

I claim:—

1. In a fire extinguisher, the combination of the body, an acid bottle pivotally supported therein, and a pull rod for normally closing the top of said bottle, said pull rod having 50 an aperture leading from the interior of the body to the air when the pull rod engages with the top of the bottle, substantially as described.

2. In a fire extinguisher, the combination 55 of a body, a cap secured to said body, an acid bottle pivotally supported by said cap, and a perforated pull rod adapted to slide through said cap and to have its lower end engage with the top of said acid bottle, substantially as described.

3. In a fire extinguisher, the combination of a body, a discharge hose, a pipe communicating with said hose, a cap screwed to the top of said body, said cap being provided 65 with curved retaining means, a frame secured to said cap and extending downwardly into said body, a weighted frame mounted in said first named frame for carrying an acid bottle, and a perforated pull rod passing downwardly through said top, and provided with 70 means for engaging the retaining means on said cap, and having at its lower end a metal plate provided with packing adapted to engage the top of the acid bottle, substantially 75 as described.

In testimony whereof, I affix my signature, in presence of two witnesses.

GEORGE W. RANKIN.
